G. G. SMITH

STARTING CRANK

Filed May 2, 1923

INVENTOR
G. G. Smith.

A. Wm. W. Wheated
ATTORNEY

UNITED STATES PATENT OFFICE.

GEORGE GREGORY SMITH, OF FRANKLIN, VIRGINIA

STARTING CRANK.

Application filed May 2, 1923. Serial No. 636,163.

To all whom it may concern:

Be it known that I, GEORGE G. SMITH, a citizen of the United States, residing at Franklin, in the county of Southampton, in the State of Virginia, have invented a certain new and useful Starting Crank, of which the following is a specification.

The invention relates to certain new and useful improvements in starting cranks of that particular type wherein is embodied safety features for preventing injury to the user under kick-back action of the engine.

In explosive engines, upon actuation of the cranking device adapted to cause rotation of the engine shaft to reciprocate the engine piston for the purpose of drawing into the cylinders and compressing therein the combustible mixture to effect the initial explosion and start of operation of the engine, it is a common experience, from one cause or another, for a reverse action of the crank shaft to occur when initial explosion takes place, which causes a severe backward force to be exerted upon the arm of the operator which is apt to cause serious injury.

It is therefore the object of my invention to provide a cranking device of the character stated and in the structure of which is included safety means whereby this kick-back action of the engine shaft may take place without any injurious effect whatever upon the arm of the operator.

With the above and other objects in view that will hereinafter appear the invention resides in those novel details of construction, combination of and arrangement of parts, all of which will be first fully described and particularly pointed out in the appended claims and illustrated in the accompanying drawing in which:

Figure 1 is a cross section taken through the crank portion of my device and looking in the direction of the engine shaft.

Figure 2 is a central longitudinal section of my device, a portion of an engine shaft being indicated in dot and dash lines and the locking key being shown retracted in dotted lines.

Figure 3 is a detail cross section taken on the line 3—3 of Figure 2.

Figure 4 is a detail perspective view illustrating the ratchet wheel member and the cam attached thereto.

Figure 5 is a detail perspective view of the locking key member.

In the drawing, 1 indicates the engine shaft of any conventional type of combustion engine and which is provided with the usual crank pin 2.

In the practical embodiment of my invention I provide a crank handle member 3 which is provided, integral therewith, with a crank portion 4 in the nature of a cylindrical shaft, in longitudinal alignment with the engine shaft (when in its operative position) and which has its end bifurcated as at 5. A stop lug 6 is secured within the inner end of the bifurcation 5 by cross pins as shown, and the said stop lug projects from the said bifurcation in a manner and for a purpose soon to be described.

Loosely mounted upon the crank portion 4, to be freely rotatable thereon, I provide a ratchet wheel 7 which is adapted to be positioned closely adjacent the stop lug 6. A cam member 8 is secured to the ratchet wheel 7, as by the use of screws 9, or made integral with the ratchet wheel, and the said cam member includes a heel portion 10 adapted to be normally held against the stop lug 6 by a light tension spring 11 secured to the posts 12 and 13 of the stop and the cam member respectively. The cam member also includes a cam face 14, the purpose of which will presently appear.

Loosely mounted upon the end of the crank portion 4, to freely rotate thereupon at intervals, I provide a crank hub 15 and the said hub is adapted to lie closely adjacent the ratchet wheel 7, to be held from longitudinal removal from the crank portion 4 thereby and by reason of the retaining plate 16 secured to the end of the crank portion 4 by the screws 17 as shown. The crank hub 15 includes a cranking extension 18 secured thereto in any desired manner, or formed integral therewith, and the said cranking extension is provided with the usual oppositely disposed crank grooves 19 adapted to engage the crank pin 2 of the engine shaft during the cranking operation.

Between the outer bifurcated end of the crank portion 4 I mount a locking key member 21 pivoted on a cross pin 22 and which is provided with a key portion for engaging a keyway 20 formed in the crank hub 15, a cutout portion 23 to accommodate free

2
rotation of the ratchet wheel 7, and a key head 24 having a bevelled face 25 adapted to be in position for being engaged at times, by the cam face 14, in a manner and for the 5 purposes soon to be described.

A spring 26, secured in any approved manner within the bifurcation 5, acts to hold the locking key member outwardly in locking relation with the key-way 20 in the 10 crank hub 15.

Pivottally mounted upon a bracket 27, secured to the engine supporting frame in any approved manner and in position for properly engaging with the ratchet wheel 7, I 15 provide a check pawl 28 which is adapted to be held in engagement with the beforementioned ratchet wheel by a spring 29.

By reason of the foregoing it will be readily apparent that by applying my improved 20 cranking device to the engine shaft of the engine adapted to be cranked in the usual manner and by applying rotary motion of the said crank in a clockwise direction, the key member 21 being in engagement with 25 the keyway 20 of the crank hub 15, the desired rotary motion will be imparted to the engine shaft.

Thus far the action of my device is exactly 30 the same as though the crank handle, the crank portion and hub were all one part as is the case in the common crank handle.

Therefor, it is understood that in this normal position of my invention the back check pawl 28 is in engagement with the 35 ratchet wheel 7 and in a manner for permitting rotation of the cam member in a clockwise direction. This rotation of the ratchet wheel in the clockwise direction, during the cranking action, is effected by the engagement 40 of the stop lug 6 with the heel portion 10 of the cam member.

Whenever a kick-back action of the engine shaft takes place the back check pawl 28 immediately acts to prevent counter-clockwise rotation of the loosely mounted ratchet 45 wheel 7 and, as the crank tends to turn in such counterclockwise direction by reason of the key and keyway connection 20-21 between the crank portion 4 and the crank 50 hub 15, such rotary motion of the crank portion 4, relative to the now stationary position of the ratchet wheel 7, causes the lug 6 to leave the heel portion 10 of the cam member, against the action of the spring 55 11, and with the effect of causing the cam face 14 of the said cam member 8 to engage the bevelled face 25 of the key head 24 to remove the key 21 from the keyway 20 to thus permit free rotation of the hub 15 60 upon the crank portion 4.

This action, of releasing the crank hub 15 from the key locked condition with the crank portion 4, is instantaneous in its action so that the said crank hub 15 may freely 65 rotate, under action of the kick-back of the

engine shaft without in any manner effecting the crank portion 4 or the arm of the operator engaging the handle portion 3. It will be readily understood that the spring connection 26 between the lug 6 and the cam member 8 will bring those parts to normal position after the parts have functioned to properly provide for the kick-back action, so that the parts may be again returned to normal position for another cranking operation.

While I have shown and described a practical embodiment of my invention I desire to have it understood that such changes in the details of construction and arrangement of parts may be made as will be desired to adapt the invention to other uses than those described herein and which come within the scope of the appended claims.

From the foregoing description, taken in connection with the accompanying drawing, it is believed that the novel details of construction, the operation and advantages of my invention will be readily apparent to those skilled in the art to which the invention relates.

What I claim is:

1. A readily removably mountable device of the class described comprising; a crank member including a handle portion and a bifurcated crank portion; a hub loosely mounted on the crank portion having an extension for engaging the engine shaft and an internal key-way; a retainer plate secured to the bifurcated crank portion to engage the hub; a stop lug secured in the bifurcation of the crank portion; a ratchet wheel loosely mounted on the crank portion, a cam member carried by the ratchet wheel and having an inwardly directed cam face and a stop heel; a spring for normally holding the cam member heel in engagement with the stop lug; a key member pivoted in the bifurcation of the crank portion and having a key portion for engaging the hub key-way, a recess for straddling the ratchet wheel and a bevelled head to be acted on by the cam face; a spring normally forcing the key member to the hub engaging position; and a spring pawl for acting on the ratchet wheel to prevent back rotation thereof.

2. A readily removably mountable device of the class described comprising; a crank member including a handle portion and a bifurcated crank portion; a hub loosely mounted on the crank portion having an extension engaging the engine shaft and an internal keyway; a retainer plate secured to the bifurcated crank portion to engage the hub; a stop lug secured in the bifurcation of the crank portion; a ratchet wheel loosely mounted on the crank portion; a cam member carried by the ratchet wheel and having an inwardly directed cam face and a stop heel; a spring for normally holding the cam

member heel in engagement with the stop lug; a key member pivoted in the bifurcation of the crank portion and having a key portion for engaging the hub keyway, a recess for straddling the ratchet wheel and a bevelled head to be acted on by the cam face; a spring normally forcing the key member to the hub engaging position; a spring pawl for acting on the ratchet wheel to prevent back rotation thereof; and a bracket carrying the pawl and having a stop portion preventing movement of the pawl beyond the depth of the ratchet wheel teeth.

GEORGE GREGORY SMITH.
